CLAIM

The ornamental design for a stackable container substantially as shown.

DESCRIPTION

FIG. 1 is a perspective view of a stackable container, according to a first embodiment;

FIG. 2 is a front view of the stackable container, thereof;

FIG. 3 is a rear view of the stackable container, thereof;

FIG. 4 is a right side view of the stackable container, thereof;

FIG. 5 is a left side view of the stackable container, thereof;

FIG. 6 is a top view of the stackable container, thereof;

FIG. 7 is a bottom view of the stackable container, thereof;

FIG. 8 is a perspective view of a stackable container, according to a second embodiment;

FIG. 9 is a front view of the stackable container, thereof;

FIG. 10 is a rear view of the stackable container, thereof;

FIG. 11 is a right side view of the stackable container, thereof;

FIG. 12 is a left side view of the stackable container, thereof;

FIG. 13 is a top view of the stackable container, thereof; and,

FIG. 14 is a bottom view of the stackable container, thereof.

The broken line elements in all views are for illustrative and environmental purposes only and form no part of the claimed design.
